[57] CLAIM

The ornamental design for table, as shown and described.

DESCRIPTION

FIG. 1 is a perspective view taken from the top, front and right side of a table embodying my new design;

FIG. 2 is a front elevational view thereof; the rear elevational view being the mirror image thereof;

FIG. 3 is a left side elevational view thereof, the right side elevational view being the mirror image thereof;

FIG. 4 is a top plan view thereof;

FIG. 5 is a bottom plan view thereof;

FIG. 6 is a perspective view taken from the top, front and right side of an alternative embodiment of my new design wherein the differences are substantially a matter length, width and height and the absence of a bottom support member;

FIG. 7 is a front elevational view thereof; the rear elevational view being the mirror image thereof;

FIG. 8 is a right side elevational view thereof, the left side elevational view being the mirror image thereof;

FIG. 9 is a top plan view thereof; and,

FIG. 10 is a bottom plan view thereof.
